DESIGN FOR A FUR COLLAR

Simon Etkin, New York, N. Y.

Application July 3, 1940, Serial No. 93,421

Term of patent 3½ years

To all whom it may concern:

Be it known that I, Simon Etkin, a citizen of the United States, residing in New York city, in the county of New York and State of New York, have invented a new, original, and ornamental Design for a Fur Collar, of which the following is a specification, reference being had to the accompanying drawing, forming part thereof.

Fig. 1 is a front view of a fur collar showing my design;

Fig. 2 is a rear view of Fig. 1, and

Fig. 3 is a bottom plan view of the fur collar shown in Fig. 1.

I claim:

The ornamental design for a fur collar, substantially as shown.

SIMON ETKIN.
